UNITED STATES PATENT OFFICE.

PATRICK B. BROWN, OF SHENANDOAH, PENNSYLVANIA.

POWER MINE-SHOVEL.

1,345,991.

Specification of Letters Patent.

Patented July 6, 1920.

Application filed June 3, 1918. Serial No. 237,915.

To all whom it may concern:

Be it known that I, PATRICK B. BROWN, a citizen of the United States, and a resident of Shenandoah, county of Schuylkill, 5 State of Pennsylvania, have invented certain improvements in Power Mine-Shovels, of which the following is a specification.

My invention relates to certain improvements in apparatus for use in mines, particularly coal mines, for removing the rock 10 from gangways, or passages.

One object of my invention is to provide a power driven shovel carried by a boom, which will discharge into a conveyer which, 15 in turn, carries the rock, or other material, to the rear of the carriage frame on which is mounted the mechanism for operating the shovel so as to enable the rock, and like material, to be discharged into a car mounted on the same rails as the car carrying the shovel structure.

A further object of the invention is to construct the boom and shovel so that the apparatus can be used in comparatively low 20 gangways.

A still further object of the invention is to construct the shovel and the conveyer so that the shovel can be moved back and discharged directly into the conveyer without 25 materially elevating the shovel.

Another object of the invention is to construct the mechanism so that the shovel can remove material at either side of the center of the apparatus and discharge the contents 30 into the hopper of the elevator. The invention also relates to certain mechanism for driving certain parts of the apparatus which will be fully described hereinafter.

In the accompanying drawings:

40 Figure 1 is a side view of my improved power mine shovel, illustrating it within a gallery of a mine;

Fig. 2 is a plan view;

Fig. 3 is an enlarged longitudinal sectional view of the front end of the machine;

Fig. 4 is a transverse sectional view on the line 4—4, Fig. 2;

Fig. 5 is a rear end view;

Fig. 6 is a diagrammatic plan view, 50 showing the driving and controlling mechanism for the several parts of the apparatus; and

Fig. 7 is a diagrammatic sectional view on the line 7—7, Fig. 6.

55 Referring to the drawings, 1 is a frame which carries the structure. This frame

has boxes 2 for the axles 3 on which are flanged wheels 4 adapted to the tracks 5 located on the floor of the gangway of the mine. 6 is the inclined frame supported 60 on the main frame 1 and this frame extends beyond the forward end of the frame 1 and to a point in close proximity to the rails 5 on which the machine is mounted and at the rear of the machine is a horizontal section 7 suitably braced and forming a continuation of the frame 6. The height of this frame 7 is sufficient to allow an ordinary mine car 8 to be located under it upon the tracks 5. The side members of 70 the frames 6 and 7 are spaced apart and located in this space is an endless belt conveyer 9, which passes around a roller 10 at the lower end of the frame 6 and a roller 11 at the rear end of the frame 7, and where 75 the conveyer changes angle there are supporting rollers 12 and 13. In the present instance, the roller 11 is the driving roller and on the spindle of this roller is a bevel gear wheel which meshes with a bevel gear 80 wheel on a longitudinal shaft 14 geared to a transverse shaft 15 which, in turn, is driven through a train of gears from a shaft 16, and this shaft is driven by a belt from a transverse shaft 17 mounted in suitable bearings at or about the center of the frame 1. This shaft is driven from any suitable motor, preferably an electric motor 49. A suitable clutch 66 is located between the pulley 64 and the shaft 17 and this 90 clutch is under the control of a lever 67 at the operator's station. By this mechanism, the conveyer travels in the direction of the arrow, Fig. 1, and transfers any rock that is discharged into the hopper 18 up to the 95 rear of the structure and discharges it into a car 8 located under the outer end of the frame 7, as mentioned above.

It will be noticed that the forward end of the conveyer extends considerably below 100 the frame 1 of the car and in close proximity to the rails 5. This construction obviates the necessity of lifting the shovel with its load to any considerable height. 19 is the shovel carried by the horizontal boom 20. This boom is suitably braced, as shown, and the inner end of the boom is pivotally mounted in a frame 21, which consists of a cross bar 22 and diagonal braces 23 and a transverse brace 24 having 105 110 bearings for a shaft 25, which also has its bearings on the inner end of the boom and

- in a box 26 which spans the conveyer. This shaft has a bevel gear wheel at the upper end which meshes with a bevel gear wheel on a screw shaft 27 extending substantially the full length of the boom 20. This screw shaft has its bearings at its two extreme ends in the boom. On the screw shaft 27 is a sliding head 28, which has a threaded opening for the passage of the screw shaft 27, so that on turning the screw shaft in one direction the trolley will move toward the pivot of the boom and when turned in the opposite direction it will move away from the pivot.
- 15 The shovel 19 is carried by an arm 29, which is pivoted to the head 28 at 30 and to the shovel at 31, and connecting the forward end of the shovel to this arm is an adjustable bar 32 pivoted at 33 to the shovel and having a series of holes adapted to receive a pin 34 so that the shovel can be adjusted to any angle desired. At the forward end of the shovel are prongs or blades 35, which may be of any shape desired and which engage the rock when the shovel is pushed forward into the mass of loose rock. At the outer end of the boom are two grooved wheels 36 and on a U-shaped bail 39 pivoted to the forward end of the shovel is a grooved wheel 38. A rope passes around the wheels from the bail to the rear of the boom and around grooved wheels 40 and 40^a on a braced frame 41, and from this frame they pass to a drum 70 on a power driven shaft 50. By actuating the drum and the screw, the shovel can be moved forward and into the mass of rock so that the rock will pass into the shovel. Then, by reversing the movement the head is moved back toward the pivot of the boom and at the same time the outer end of the bucket is raised so that the bucket will pass over the edge of the hopper 18, as shown by dotted lines, Fig. 1. The shovel 19 has a rear door 42 pivoted at 43 to the upper end of the shovel and this door is normally closed by a suitable latch 44 to which is attached a chain 45 secured to a trigger 46 pivoted to the arm 29. On the forward brace 47 of the boom is a pin or lug with which the trigger engages when the shovel is in the position illustrated by dotted lines Fig. 1, so as to release the door and allow the rock, or other material, to be discharged from the shovel and into the hopper 18 and onto the endless belt 9. This belt is at such an angle that the rock will be carried by the belt to the discharge point.
- It will be seen by this construction that the ceiling γ of the gallery can be comparatively low, as the boom is fixed as regards any vertical movement, and as the shovel is elevated just enough to give it clearance to move from its forward to its rear position, very little space is required.
- 65 The great difficulty in manipulating

power driven shovels prior to my invention was the fact that considerable head room was necessary to provide for the elevation of the boom and the movement of the shovel. It is very costly to cut these galleries in the stone and by the use of my invention they need not be higher than is absolutely necessary for the proper working of the mine cars.

The vertical shaft 25 which operates the screw 27 is geared to a transverse shaft 25^a which is, in turn, geared to a longitudinal shaft 51 through bevel gears and is geared, in turn, to a shaft 51^a and this is geared through clutch mechanism 65 to the transverse shaft 50. This shaft is geared to the shaft 17 by gearing 68. The clutch 65 is actuated by a lever 69 through suitable mechanism shown in diagram, Fig. 6. As the clutch 65 is a double face clutch, the screw will remain stationary when the sleeve is in the central position, and when moved to one side the screw is turned so as to move the head forward and when moved to the opposite side the screw is reversed, causing the head to be retracted. A clutch 71 is located between the drum 70 and the shaft 50 and this clutch is controlled by a lever 72. Engaging the drum is an ordinary strap brake 73, which is controlled by a lever 74 so that the drum can be held by the operator in any position desired in order to position the shovel properly. Extending around the bull wheel 52, which controls the lateral movement or swing of the boom, is a wire rope 53, which passes around guide wheels 75 to a drum 76 and this drum is mounted on a shaft 77, which is geared to a shaft 78 which, in turn, is geared to the shaft 50 through a double faced clutch 79 controlled by a lever 80. 81 is an electric switch at the operator's station so that the operator standing at a given position can control all of the mechanism of the machine.

In the present instance, the machine is self propelled and the axles 3 are driven through two longitudinal shafts 56 which are, in turn, geared to a shaft 57 which is driven by a chain which passes around a sprocket wheel 50^a on the shaft 50. A clutch 57^a is located between the gearing driving the axles and the shaft 57 and this clutch is controlled by a lever 82 at the operator's station.

While I have described a given mechanism for controlling the several devices, this mechanism may be modified without departing from the essential features of the invention.

At each rear corner of the frame 1 is a jack 61 provided with an extension 62 having a head 63 which is arranged to engage the roof γ of the gallery so as to lock the machine in position and to resist the pres-

110

115

120

125

130

sure of the shovel in engaging the loose material. These jacks may also be at the forward end of the frame, if found desirable.

58 is an electric service wire hung from the roof of the gallery and on the machine is a trolley pole 59 having a trolley 60 arranged to engage the wire.

By the above construction, it will be seen that I am enabled to construct a mine shovel

10 which can be adjusted in galleries having comparatively low ceilings and as the boom is horizontally mounted and is fixed against vertical movement, and by the arrangement of the screw, or its equivalent, on the boom, 15 the connection between the shovel and the boom can be comparatively short. This is due to the fact that in order to discharge the shovel into the hopper of the conveyer very little elevation is necessary as the receiving end of the conveyer extends to a point near the floor of the conveyer, being 20 designed to elevate the material properly and to discharge it into a car at the rear. This shovel structure is mounted on the same 25 tracks which are used for the mine cars.

By turning the boom horizontally on its pivot the shovel can remove rocks, or other material, from an extended area on either side of the tracks.

30 I claim:

1. The combination in a power mine shovel, of a frame; a centrally located box at the forward end of the frame open at its under side; an inclined belt conveyer mounted on the frame and extending through the opening in the box to a point beyond the rear end of the frame; a vertical shaft; a horizontal boom, the said shaft being supported by the box; means for supporting 35 the upper end of the shaft and boom; means for moving the boom laterally; a head; a screw for traversing the head to and from the pivot of the boom; a shovel pivoted to the head and connected to the boom so that 40 it can be moved rearward from its digging position with its load in order to discharge its load onto the conveyer.

2. The combination in a power mine shovel, of a car recessed at the forward end; 45 a box open on the under side and spanning the recess; a vertical shaft supported by the box; means for supporting the upper end of the shaft; a horizontal boom mounted to swing on the shaft as a center; a screw shaft extending longitudinally on the boom and adapted to be driven from the vertical shaft; an inclined elevating conveyer extending through the opening in the box and

in the recess in the front of the car and terminating at a point near the floor; a head 60 on the boom arranged to be traversed by the screw shaft; and a shovel pivotally mounted on the head and so arranged as to receive material and on its backward movement to discharge material onto the conveyer, said 65 conveyer having an extension at the rear of the car of a sufficient height to allow it to discharge into a mine car.

3. The combination in a mine shovel, of a car having wheels; a motor; a shaft 70 geared to the motor; a second shaft geared to the first mentioned shaft; a boom at the forward end of the car; a shovel suspended from the boom; a screw on the boom controlling the movement of the shovel; gearing between the screw and the secondary shaft by which said screw is turned; a clutch for changing the direction of movement of the screw; a rope extending to the end of the boom and attached to the shovel; 80 a drum on the secondary shaft for the rope; a clutch controlling the movement of said drum; a drum driven from the secondary shaft and having clutch mechanism whereby the movement can be reversed; a bull 85 wheel on the boom; a rope extending around the bull wheel to the drum so that in operating the drum the boom can be turned laterally on its pivot; and means, operated from the first mentioned shaft, for driving the 90 conveyer.

4. The combination in a mine shovel, of a frame recessed at the forward end; a box spanning the recess; an inclined conveyer mounted on the frame and extending 95 through the space under the box and through the recess; a vertical shaft mounted on the box; means for bracing the upper end of the shaft; a horizontal boom pivoted to swing on the shaft but having no vertical 100 movement; a screw extending longitudinally of the boom and driven from the said vertical shaft, said boom being in close proximity to the roof of the mine gallery; power means for moving the boom laterally; a head on the boom controlled by the screw shaft; a shovel pivotally mounted on the head and connected to the boom; and means for causing the shovel to discharge 105 its load when retracted, the conveyer being 110 in such position as to receive the load as it is discharged and to carry it over the frame and discharge it at the rear end thereof.

In witness whereof I affix my signature.

PATRICK B. BROWN.
